1 Claim. (Cl. 313—49)

An electric lamp in which the lamp cap and the portion of the lamp vessel surrounded by it are secured together by means of a metallic connecting body is known. This structure is used, for example, for the purpose of correctly adjusting the filament inside the lamp with respect to the lamp cap. This may be important, for example, if the relevant lamp is intended for the lighting of vehicles or projection and, during operation, must occupy a predetermined position relative to the associated optical means in order to obtain a maximum effect.

The present invention relates to an improvement in such a lamp whereby the advantage is obtained that the envisaged adjustment may be effected within wide limits in both the transverse direction and the longitudinal direction. To this end, a lamp according to the invention is characterized in that the connecting body between the lamp cap and the portion of the lamp vessel surrounded by it has at least two strip-shaped parts bridging the distance between the inner side of the lamp cap and the portion of the lamp vessel surrounded by it, the larger transverse dimension of said parts being equally directed as the axis of the lamp cap.

Thus, the advantage is obtained that there is not only a possibility of displacement in the direction of the axis of the lamp cap between the latter and the lamp vessel, but also as a result of the deformability of the strip-shaped parts, said vessel is adjustable over a comparatively large distance in the transverse direction relative to the lamp cap and can readily be fixed in position.

Although the connecting body could be formed by a sleeve tightly surrounding the seal and to which the strip-shaped parts are attached, for example by soldering, in one advantageous embodiment of the invention it is preferable to build up the whole of the connecting body of substantially identical structural parts made from metal strips.

If there is a risk that the lamp once adjusted tends to move with respect to the lamp cap, for example due to vibration, a risk resulting from the deformability of the strip-shaped parts, it is in another embodiment of the invention preferable to fill the space between the inner side of the lamp cap and the outer side of the portion of the lamp vessel located inside the lamp cap or the connecting body at least in part with a solidifying mass, such as cement.

In order that the invention may be readily carried into effect, several embodiments thereof will now be described in detail, by way of example, with reference to the accompanying diagrammatic drawings, in which:

FIGURE 1 is an elevational view of a first embodiment of the lamp according to the invention;

FIGURE 2 shows the same lamp, partly in side view and partly in section;

FIGURE 3 is a sectional view of the lamp of FIGURE 2, taken on the plane III—III;

FIGURE 4 is a perspective view of one of the parts of the connecting body used in the lamp shown in FIGURES 1, 2 and 3;

FIGURE 5 shows, partly in side view and partly in section, a second embodiment of the lamp according to the invention;

2

FIGURE 6 is a sectional view taken on the plane VI—VI of FIGURE 5 and

FIGURE 7 shows one of the parts of the connecting body as used in the embodiment of the lamp shown in FIGURES 5 and 6.

The lamp shown in FIGURES 1 and 2 comprises a bulb 10 closed at each end by seals 11 and 12 respectively. A filament 13 is mounted in the lamp between supporting wires 14 and 15. Molybdenum foils 16 and 17 respectively are included in the said supporting wires. The bulb has a protrusion which is the sealing tip of an exhaust tube 18.

The lamp is provided with a cylindrical metallic cap 19 for fixing on a lamp holder, not shown. To this end, pins 20 and 21 are provided. The current supply wire 15 is secured to a central contact 22 of the lamp in the manner usual with incandescent lamps. From FIGURE 1 it can be seen that the supporting wire 14 is secured to another supporting wire 23 which extends along the axis of the lamp vessel and is connected to the cap 19 in an electrically conductive manner.

Two of the structural parts shown in FIGURE 4 are fixed on the seal 12 so as to intimately surround it. The structural part shown in FIGURE 4 has apertures 24 and 25 into which fit glass projections 26 and 27 provided on the seal 12. The two structural parts 28 and 29 are connected together by welding or soldering through strip-shaped zones indicated by 30 and 31 in FIGURE 3. The connecting body comprising the parts 28 and 29 is thus fixed on the seal 12 in a reliable manner. Strip-shaped portions 32 and 33 of the two structural parts are resilient and their free ends are spaced from each other a distance greater than the internal diameter of the cap 19. When moved towards each other these ends can be slipped in this position into the lamp cap 19, thereby engaging the inner periphery thereof. Now, the situation shown in FIG. 3 is reached. Next the distance between the center of the filament 13 and a reference surface on the lamp cap 19 may be adjusted. This is effected by displacing the lamp vessel, together with the connecting body, in the longitudinal direction inside the lamp cap. The reference plane may be formed, for example, by the center lines of the pins 20 and 21. To adjust the filament 13 also in the transverse direction, the free portions of the strip-shaped projections are bent. Since the longer dimension of these strips is equally directed as the longitudinal axis of the lamp cap, such bending results in a lateral displacement of the lamp vessel in the lamp cap. In the ultimate position the portions of the projections which engage the inner side of the lamp cap may be secured to the lamp cap by welding or soldering.

In the embodiments shown in FIGURES 5, 6 and 7, the structures of the lamp vessel 40 and the lamp cap 41 are identical with those shown in FIGURES 1, 2 and 3. The connecting body comprises two parts also in this case, but has a shape slightly different from the connecting body shown in FIGURES 1 to 4. Each part of the connecting body has, as may especially be seen from FIGURE 7, a flat portion 42. This may be provided with apertures 43 and 44 to allow the passage of glass projections 45 and 46 provided on a seal 47 of the lamp. Each structural part furthermore has two strips indicated by 48 and 49 in FIGURE 7. The central portion 42 has, at its upper side, tongues 50a-50b and 51a-51b respectively which have been bent twice. The portions 50a and 51a of the tongues form part of the envelope surrounding the seal 47. The portions 50b and 51b of the said tongues, which are further remote, serve to secure together the opposing structural parts by a soldering or welding operation. This may be seen from FIGURE 6.

Since with this structure the same possibility of adjustment of a lamp vessel relative to the lamp cap may be obtained as with the structure shown in FIGURES 1 to 4, this adjustment will not be described further.

If, for example, due to mechanical loads, vibration and the like, there would be a risk of the lamp vessel not permanently occupying the position once adjusted relative to the lamp cap, the lamp vessel may be fixed relative to the lamp cap by providing a solidifying mass, such as cement, in the space which subsists in the lamp cap after the provision of the seal and the connecting body. 5

It will be evident that the seal of the lamp may have any cross-section differing from the substantially rectangular cross-section shown.

What is claimed is:

An electric lamp comprising a bulb having at least one projection thereon, a filament, first means mounting said filament within said bulb, a lamp cap, and second means mounting one end of said bulb in said lamp cap, said second means including two strip-shaped parts positioning said one end of the bulb in spaced relationship with the inner side of said lamp cap, one of said strip-

shaped parts being provided with an aperture through which the projection of said bulb protrudes, said strip-shaped parts being provided with bent tongues in adjacent pairs that abut each other and are secured together.
